Application June 30, 1941, Serial No. 400,386

15 Claims. (Cl. 164—23)

This invention relates to improvements in presses and is herein illustrated as embodied in a clicking machine of the type disclosed in United States Letters Patent No. 921,503, granted May 11, 1909, on an application filed in the name of Arthur Bates. It is to be understood, however, that in various novel and useful aspects the invention is not limited to machines of the particular type illustrated.

In the use of presses of the above-mentioned type, each of which is commonly provided with a member for applying pressure to a workpiece mounted on a work support, it sometimes happens that the press becomes stalled because the presser member is unable to complete its operative stroke. When this occurs it is, of course, very difficult to release the parts without substantially dismantling the machine. Usually, the work support, which of necessity is so designed and supported that it will readily sustain the heavy pressure applied to it, is immovable in the heightwise direction of the machine so that a stalled presser member cannot be released by a lowering of the work support. In cases where the work support is provided with mechanism for adjusting it in the direction of pressure application, that mechanism frequently becomes so sprung and frozen when the presser member is stalled on the work support that a release of the presser member by the work support adjusting mechanism is practically impossible.

It is, therefore, an object of this invention to provide an improved press having means for easily and quickly releasing the machine parts when the press has become stalled and for easily and quickly adjusting the work support in the direction of pressure application.

In accordance with an important feature of the invention, the illustrated press is provided with fluid pressure means for moving the work support into its operative pressure sustaining position and maintaining it in that position. This operative position of the work support is determined by an adjustable stop against which the work support is moved and held by the fluid pressure means.

In accordance with another feature of the invention, the illustrated press is provided with a manually operable valve for controlling the flow of a suitable pressure medium, such as pressure oil, toward and from fluid pressure mechanism. In the position of pressure application of the valve the work support is effectively held in its operative pressure sustaining position by the fluid pressure means, whereas on movement of the

valve to its exhaust position the work support is quickly moved to its inoperative position so that in the case of a stalled presser member the sprung machine parts may quickly be released without any effort on the operator's part and without any danger of breaking the machine parts or any necessity of disconnecting them.

Still another feature of the invention is a valve arrangement according to which the valve may be moved into two different exhaust positions. In one exhaust position the fluid pressure means is immediately and fully released. This particular valve position will be selected when a quick movement of the work support into its inoperative position is desired to release the presser member, if stalled. In the other exhaust position of the valve the fluid pressure is only slowly and partially released, the release being just sufficient to enable the operator to adjust the stop against which the work support is moved by the fluid pressure means.

In accordance with a further feature of the invention, the illustrated press is provided with a pump for supplying the pressure medium and an accumulator in which the pressure medium is stored. The press-operating mechanism is provided with means which during each cycle of operation of the press operates a pump actuating mechanism so that the latter produces one compression stroke of the pump during each cycle of operation of the press.

Other objects of the invention and features of construction will be apparent from the following description and will be pointed out in the claims.

In the drawings,

Fig. 1 is a front view, partly in section, of the lower portion of a press in which the present invention is embodied;

Fig. 2 is a detail view of a manually operated valve controlling mechanism;

Fig. 3 is a left-hand side elevation of the machine, partly in section and with certain parts broken away;

Fig. 4 is a detail view on an enlarged scale of a portion of the mechanism shown in Fig. 3 for adjusting a stop determining the operative position of the work support of the machine;

Fig. 5 is a view partly in rear elevation and partly in section illustrating the pump, the accumulator, and the mechanism for operating the pump;

Fig. 6 is a detail view of ducts in the pump casing;

Fig. 7 is a detail view of a casing containing a

valve controlling the flow of pressure fluid toward and from the fluid pressure means;

Fig. 8 is a section taken on the line VIII—VIII of Fig. 7, showing the valve in its normal position of pressure application;

Fig. 9 is a view similar to Fig. 8, but showing the valve in its partial exhaust position;

Fig. 10 is a view similar to Fig. 8, but showing the valve in its full exhaust position;

Fig. 11 is a diagrammatic view illustrating the fluid pressure operating means and the valve for controlling its operation.

The illustrated press comprises a C-shaped frame member 20 (Fig. 3), containing bearings for the upper and lower ends of a vertical column or post 22 which is adapted to be rotated manually to bring a presser arm or beam 24, fixed to the post, into any desired position over a work support herein illustrated as a cutting block or bed 26.

The post 22 and presser arm 24 are reciprocated vertically by mechanism of the nature described in the aforementioned United States Patent for the purpose of causing the presser arm 24 to apply pressure to a die placed on a work-piece supported on the block 26. The mechanism for actuating the post 22 and presser arm 24 includes a driven pulley 28 (Fig. 3) and a clutch 29. The clutch is connected by a clutch tripping link and lever mechanism 30 and 31 to a handle 32 on the presser arm 24. The handle 32 which is grasped by the operator serves to rotate the presser arm 24 as well as to trip the clutch 29 to initiate an operative cycle. The clutch, when tripped, transmits the motion of the continuously rotating pulley 28 to a horizontal shaft 34 mounted in bearings in the frame member 20 and carrying at its inner end an eccentric 36 (Figs. 1, 3, and 5) surrounded by a strap 38 into which is threaded a rod 40. The rod 40 serves to impart up and down motions to the post 22, and to that end it is connected at its upper extremity to the upper end of the post 22 by a universal joint (Fig. 3) of well-known construction.

For supporting the cutting block 26 and the fluid pressure means for moving the cutting block into its elevated operative position and for maintaining it in that position during the operation of the machine, the illustrated machine is provided with a casting 42 (Figs. 1 and 3) having at its rear face a projection or tongue 44 (Fig. 3) fitting into a groove 46 provided in a vertical front face of the frame member 20. The casting 42 and the entire movable assemblage of cutting block 26 and block elevating means are adapted to be rotated as a unit laterally of the machine about a substantially vertical axis for the purpose of exposing the inner end of the shaft 34 and the eccentric 36 to facilitate the installment or the removal of the latter members. To that end, the casting is provided with a laterally extending portion 48 (Fig. 1) having bearing members 50 in which is received a substantially vertical shaft 52, the shaft being secured in the bearing members by screws or the like. Surrounding the shaft 52 and located intermediate the two bearing members 50 is a bearing 54 which is bolted to the frame member 20. The upper portion of the shaft 52 is seated in a bearing provided in the lower face of a carrier or table 56 on which the cutting block 26 is mounted. In its normal operative position the casting 42 is held in place by suitable means such as bolts 55 (Fig. 3).

During the operation of the illustrated ma-

chine, the block 26 and carrier 56 are acted upon by a pressure medium, for example oil, which causes these two members to be held in their operative position after they have been moved into that position under the force of the pressure medium. The operative position of both the block 26 and carrier 56 is adjustably determined. This arrangement of elevating the cutting block 26 into an adjustably determined position and holding it in that position during the normal operation of the machine has the advantage of permitting quick partial release of the work support from its operative position when an adjustment of that position becomes necessary or desirable and still further for a quick dropping of the cutting block to its lowermost position when the presser member 24 has become stalled on the block 26.

For the purpose in view, the carrier 56 is provided with a downwardly extending, hollow plunger 60 (Fig. 3) which is slidably received in a cylindrically shaped portion 62 of the casting 42. A spring-pressed pin 58 (Fig. 1), carried by the laterally extending portion 48 of the casting 42, normally engages a socket provided in a portion of the carrier 56 to prevent relative rotary movement between the plunger 60 and the cylinder 62. The plunger 60 is provided at its upper portion with a peripheral shoulder 63 which in the lowermost position of the movable assemblage, composed of block 26, carrier 56, and plunger 60 is seated upon a rim at the upper end of the cylinder 62 (see Fig. 3). The lower portion 64 of the plunger 60 is of reduced diameter to provide between the plunger 60 and the inner wall of the cylinder 62 an annular chamber 66 into which fluid under pressure is admitted through a port 68 to elevate the plunger 60 relatively to the cylinder 62. The annular chamber 66 is sealed by gaskets 70 secured to shoulder portions of the plunger 60 and the cylinder 62, respectively, to prevent the pressure fluid contained in the annular chamber from leaking out along the inner wall of the cylinder 62. As illustrated, the reduced lower portion 64 of the plunger 60 extends through an opening in the bottom of the cylinder 62 and has a close fit therein.

For determining the elevated operative position of the movable assemblage there is provided an adjustable stop serving to limit the upward movement of the plunger 60, the plunger 60 being held against the stop by the fluid pressure after it has been elevated. To that end, there is provided a cap or lid 74 (Fig. 3) closing the upper end of the hollow plunger 60. Secured to the lower face of the lid by screws or the like is a downwardly extending cylindrical member 76 (Figs. 3 and 4) having its lower end open. Near its lower end, the cylindrical member 76 is provided with shoulders 78 carrying ball bearings 80 on which is rotatably supported a gear 82. The gear 82 has an elongated hub which has a sliding fit on a sleeve 84 provided with an internal thread. The sleeve 84 is threaded upon a long screw 86 extending downwardly through the entire length of the plunger 60 and the bottom thereof, the screw 86 being fixed, as will be explained, to the casting 42. To permit the gear 82 and the sleeve 84 to rotate together while at the same time permitting relative movements of the gear 82 and sleeve 84 along their axis of rotation, the gear 82 is provided with a key 88 engaging a keyway provided in the sleeve 84. The upper end of the sleeve 84 has a flange 90 and this flange acts as

an adjustable stop for the movable assemblage when the pressure fluid is admitted through the port 68 to the annular chamber 66. From the inoperative positions of the parts illustrated in Figs. 3 and 4, the plunger 60 and with it the cylindrical member 76 and gear 82 are elevated upon admission of the pressure fluid to the chamber 66 until the upper end of the gear 82 abuts the flange 90 of the sleeve 84, thereby terminating the upward movement of these members and determining the upper elevated position of the cutting block 26. The sleeve 84 is normally held stationary because of its threaded engagement with the stationary long screw 86. In order to adjust the sleeve 84 and particularly the flange 90 provided thereon heightwise so as to vary the operative position of the cutting block 26, the gear 82 is meshing with a vertical gear 92 secured to the inner end of a shaft 94 (Fig. 1) rotatably mounted in bearings provided at the lower face of the carrier 56 and having on its outwardly projecting end a hand wheel 96, by means of which the shaft 94 may be rotated to rotate the gear 82 and the sleeve 84 rotatably connected to the gear by the key 88, with the result that the sleeve 84 is lowered or raised on the upper extremity of the stationary screw 86. It is understood, of course, that this adjustment can take place only after at least a partial release of the pressure fluid from the chamber 66.

As previously mentioned, the screw 86 extends through the bottom of the hollow plunger 60. The lower end of the screw 86 is mounted in a bearing provided at the forward end of a bracket 98 bolted to the casting 42. The bearing in the bracket 98 is provided with a key engaging a keyway in the screw 86 to prevent the latter's rotation. A nut 97, threaded upon the lower extremity of the screw 86 and abutting the bracket 98, serves to hold the parts in place.

In order to lend additional support to the fluid pressure means so far described, the lower end of the plunger 60 is connected by two telescopically adjustable braces 99 (Fig. 1) to lugs on the lower face of the carrier 56.

The means for supplying and controlling the pressure fluid in the illustrated machine will now be described. As previously mentioned, the mechanism for actuating the presser arm 24 includes an eccentric strap 38 (Fig. 5). This strap is provided with a laterally extending projection 100 which upon up and down movement of the strap, as a result of a single revolution of the shaft 34, serves to actuate a pump for supplying the pressure fluid, preferably oil. There is also provided an accumulator in which the pressure fluid is stored, and mechanism for controlling the flow of the operating fluid from the accumulator to or from the pressure chamber 66, thereby causing the cutting block 26 to be moved upwardly to its operative position relatively to the presser member 24 or to be lowered out of operative position. On downward movement of the strap 38, the projection 100, which engages a laterally extending arm 102 on a pump actuating lever 104, causes a swinging movement of this lever in a counter-clockwise direction (Fig. 5) about its supporting shaft 105 which is rotatably mounted in suitable bearings provided in the machine frame. The pump comprises a casing 106 integral with one wall of an oil reservoir 108 secured by bolts 109 to the frame member 20, and a hollow plunger 110 arranged to be reciprocated in a horizontal, cylindrical bore in the casing 106. The bore is closed at its forward end by a cap 75

provided with an opening through which the closed left-hand portion (Fig. 5) of the plunger 110 extends. The lower end of the lever 104 engages the left-hand end of the plunger 110. A spring 112, the left-hand end (Fig. 5) of which extends into the plunger and is seated therein, and the right-hand end of which bears against the right-hand end of the horizontal bore in the pump casing 106, tends to move the plunger 110 outwardly, i. e., toward the left of Fig. 5. The hollow interior of the pump casing 106 is in communication with a substantially vertical duct 114 provided in a block 115 integral with the pump casing and the bottom of the reservoir 108. There is provided a pressure relief valve 113 of well-known construction which automatically opens and permits oil to spill over into the reservoir 108 when a predetermined maximum pressure has been reached inside of the pump casing 106 and duct 114. The lower end of the duct 114 is provided with a ball valve 116 and is connected by an intake port 118 with the reservoir 108. Accordingly, upon outward movement of the plunger 110 toward the left of Fig. 5 under the pressure of the spring 112, the plunger 110 is on its suction stroke, as a result of which the ball valve 116 is opened to admit oil from the reservoir 108 into the duct 114 and the pump casing 106. Upon movement of the pump actuating lever 104 in a counter-clockwise direction, as viewed in Fig. 5, during the downward movement of the eccentric strap 38 the plunger 110 is moved inwardly against the pressure of the spring 112 to compress the oil contained in the casing 106 and duct 114 thereby closing the ball valve 116. The fluid under pressure is permitted to escape through a passage 120 in the block 115 and spring-pressed check valve 122 into a passage 124 also provided in the block 115. The lower end of the passage 124 is the intake for the already mentioned accumulator, also shown in section in Fig. 5 of the drawings. The accumulator comprises a cylindrical member 126 open at its upper end and closed at its lower end and provided at its upper extremity with a flange or rim bolted to the bottom of the reservoir 108. A two-part plunger 128, comprising two nested cup-shaped members, has a sliding fit in the cylinder 126. The plunger 128 is hollow, its upper end is closed and its bottom end is open. Seated in the interior of the plunger 128 is the upper end of a comparatively heavy spring 130, the lower end of which is seated upon the bottom of the cylinder 126. Threaded into the bottom of the cylinder 126 is a rod 132 which extends part way through the spring 130 and serves to limit the downward movement of the plunger 128 under the pressure of the oil being pumped into the upper end of the accumulator. As illustrated in Fig. 3, the lower portion of the cylinder 126 is connected by a pipe 134 with the reservoir 108 so that any oil, which may have leaked past the plunger 128 into the lower portion of the cylinder 126, may be forced back into the reservoir 108. The upper end of the accumulator is in communication with a passage 136 (Figs. 3 and 5) provided in the bottom of the reservoir 108, the outer end of this passage being provided with a nipple 138 to which is fitted one end of a pressure resisting hose, the other end of which is connected to an inlet passage 140 of a valve casting 142 (Figs. 1, 7 to 10) secured by bolts 142 to the casting 42.

As already mentioned, the flow of pressure fluid to and from the pressure chamber 66 of the cylin-

der 62 is specially controlled and for that purpose there is rotatably mounted in a bore provided in the valve casing 140 a cylindrical valve member 144 (Figs. 8 to 10) which is provided in its surface with two recesses 146, 147 serving to establish communication between various oil passages leading into or out of the valve casing, as will be described. The position of the valve member 144, illustrated in Fig. 8, is its normal position in which communication is established between the accumulator through the inlet passage 148, recess 146, and an outlet passage 150, and the pressure chamber 66, the passage 150 being connected by a hose to the port 68 of the pressure chamber 66. In the upper portion of the valve casing 140 is provided a spill-over tank 152 into which oil under pressure is returned from the chamber 66 upon movement of the valve 144 into exhaust position. This chamber 152 is connected by a duct 154 to the bore in the valve casing. Moreover, the valve casing is provided with a duct 156 communicating with a duct 158 through which ducts the oil is caused to flow back from the chamber 152 to the reservoir 108. The duct 158 is connected by means of a nipple and T-fitting 160 and hose to a nipple 161 (Fig. 3) communicating with the reservoir 108.

As illustrated in Figs. 9 and 10, the valve 144 may be rotated into two different pressure release or exhaust positions. In the position illustrated in Fig. 9, the duct 154 is opened partly to the duct 150 by the agency of the valve recess 146. Accordingly, the oil contained in the chamber 66 is forced under the heavy pressure of the machine parts, particularly the block 26, the carrier 56, and the plunger 60, back through the ducts 150 and 154 into the chamber 152. In view of the restricted passage of the oil through the only partially opened duct 154, the release of the pressure is very gradual and slow. As a matter of fact, only so much pressure is released as is necessary to facilitate a rotation of the gear 82 by a rotation of the hand wheel 96 to adjust the sleeve 84 and stop flange 90 in a heightwise direction. After this adjustment has been made, the valve is immediately returned into the position illustrated in Fig. 8 so that full pressure may quickly be restored in the chamber 66 and, consequently, very little time is wasted in making this adjustment.

If, however, it should become necessary to move the block 26 into its lowermost position, for example to release the presser arm 24 after it has become stalled on the block 26, the valve 144 is moved into its full pressure release position, illustrated in Fig. 10, in which the duct 154 is opened wide to the duct 150 so that the oil, contained in the chamber 66, may be immediately and quickly released from the chamber 66 and caused to flow into the chamber 152, thereby dropping the plunger 60 and block 26 into their lowermost positions, as determined by the engagement of the shoulder 63 with the rim at the upper end of the cylinder 62 (see Fig. 3). It is understood that after the presser arm 24 has been released by dropping the block 26, pressure is restored to the chamber 66 and the block 26 is elevated by turning the valve 144 back into the position illustrated in Fig. 8. As further shown in Fig. 8, in the normal position of pressure application of the valve 144 the duct 154 is in communication through the recess 147 of the valve 144 with the passages 156 and 158 so that the oil contained in the chamber 152 against the pressure of the body of air behind it, which has

been somewhat compressed upon forcing the oil from the chamber 66 into the chamber 152, is now caused to flow out of the valve casing back into the reservoir 105.

5 To operate the valve member 144, as described, it has an outwardly extending stem portion 162 (Figs. 1 and 7) connected by a universal joint with one end of a rod 164, the other end of the rod being connected by a universal joint to a 10 stub shaft 166 (Figs. 1 and 2) rotatably mounted in a bracket 168 which is bolted to the carrier 56. Secured to the outer end of the shaft 166 is an arm 170 (Fig. 2), the free end of which is connected by a link 172 to a hand lever 174. The hand lever 174 is mounted on a stub shaft 176 rotatable in the bracket 168. A second hand lever 178 is loosely mounted on the shaft 176. The hand lever 178 has a downwardly extending projection 180 which is adapted to engage a pin 182, by which pin the link 172 is connected to the first-mentioned hand lever 174. Secured in the bracket 168 is a stop pin 184 for arresting the hand lever 178 after it has been moved downwardly from its position illustrated in Fig. 1. 20 To terminate the downward movement of the hand lever 174, the bracket 168 is provided with a shelf 186 which is engaged by a stop pin 188 carried by the hand lever 174. Moreover, to determine the uppermost inoperative position of the hand lever 178, the shelf 186 carries a stop pin 190 which is adapted to engage a tail piece 192 provided on the hand lever 178. To move both hand levers 174 and 178 into their upper inoperative positions, there is mounted on the 30 shaft 166 a torsion spring 194, one end of which abuts a pin 196 which acts as a pivot connection between the arm 170 and the link 172, and the other end of which spring abuts a pin 198 which may be inserted into any one of several sockets 35 40 provided in the bracket for the purpose of adjusting the tension of the spring. The spring 194 tends to move the link 172 upwardly, thereby moving the hand lever 174 upwardly which, by reason of the engagement of the pin 182 with the projection 180 on the hand lever 178, also elevates the latter hand lever 178 into its normal inoperative position.

If it is desired to move the valve member 144 from its normal position of pressure application, 50 illustrated in Fig. 8, into its partial pressure release or exhaust position, illustrated in Fig. 9, for the purpose of making an adjustment of the stop flange 90 and sleeve 84, the hand lever 178 is depressed until it engages the stop pin 184 secured to the bracket 168. In doing this, the valve 144 is rotated into the position shown in Fig. 9 and this by reason of the fact that, due to the engagement of the projection 180 on the hand lever 178 with the pin 182 of hand lever 174, the latter hand lever has been partially depressed, thereby rotating, through the agency of the link 172 and arm 170, the shaft 166 and the valve 144. If, on the other hand, it is desired to move the valve member 144 from its normal position of pressure application, shown in Fig. 8, into 55 60 65 70 75 is full pressure release position, shown in Fig. 10, only the hand lever 174 is depressed which, as illustrated in Fig. 1, is so mounted that it clears the fixed stop pin 184. Accordingly, the hand lever 174 may be further depressed until the pin 188, carried by it, engages the shelf 186. In this position of the hand lever 174 the valve 144 has been rotated into its full pressure release position, shown in Fig. 10.

For the sake of making a complete and some-

what simplified showing of the entire fluid pressure mechanism of the illustrated machine, including the valve mechanism, Fig. 11 of the drawings shows diagrammatically the various parts of the fluid pressure mechanism in their mutual relationship. The pump, indicated in Fig. 11 by P, has an intake connected with the oil reservoir 108. The pressure side of the pump is connected with the accumulator identified by the cylinder 126 and piston 128. As previously explained, the accumulator is connected to the valve casing 140. In the normal position of the valve 144 shown in Figs. 8 and 11 the pressure fluid is caused to flow through the valve into the annular pressure chamber 66 where it is active to elevate the plunger 60, the carrier 56, and the cutting block 26, as previously described.

The fluid pressure is sufficiently strong effectively to maintain the block 26 in its pressure sustaining position, particularly when the presser arm 24 is operative to apply pressure upon the work supported on the block 26. It is to be understood, however, that since an open connection is maintained between the accumulator and the chamber 66 in the position of pressure application of the valve 144, excessive pressure applied by the presser arm 24 to the block 26 may be taken up by the accumulator, in which case the spring 130 may be caused to yield somewhat.

In the position of pressure application of the valve any oil contained in the chamber 152 above the valve is returned through ducts 154, 156 and 158 to the reservoir 108. Rotation of the valve into its partial or full exhaust positions, shown in Figs. 9 and 10, disconnects the cylinder 62 from the accumulator and establishes communication between the cylinder 62 and the chamber 152 with the result that the pressure fluid contained in the cylinder 62 spills over into the chamber 152, thus releasing the pressure in 40 the chamber 66 and lowering the carrier 56 and cutting block 26.

It is possible that after the full or partial release of the hydraulic pressure in the chamber 66 for the purpose of lowering the cutting block 26, the pressure of the oil stored in the accumulator is insufficient to restore the cutting block to its elevated operative position with the result that the machine, due to the improper position of the cutting block, cannot be operated and, hence, the pump cannot be operated to replenish the supply of pressure oil in the accumulator and to load the spring 130. To cope with this situation, the illustrated machine is provided with means for manually operating the pump, while the machine is at rest, to store pressure fluid in the accumulator in an amount sufficient to raise the cutting block so that the machine operation may be resumed. To this end, the above-described shaft 105 carrying the pump operating lever 104 has secured to it an arm 202 (Fig. 5), the lower surface of which is engaged by one arm of a bell-crank lever 204 pivotally mounted on a stud 206 secured in a bracket 208 bolted to the frame member 20. A spring 210, secured at one end to the frame member 20 and at the other end to the right-hand arm (Fig. 5) of the bell-crank lever 204, tends to rotate the bell-crank lever 204 in counter-clockwise direction, as viewed in Fig. 5, into inoperative position. For the purpose of swinging the bell-crank lever 204 in clockwise direction to impart a counter-clockwise movement to the arm 202 and lever 104 and thereby to operate the pump, the above-mentioned right-hand arm of the bell-crank 75

lever 204 is provided with a socket 212 in which is secured one end of a rod 214. As will be seen by manually depressing the rod 214 repeatedly, the pump 110 is operated to store up pressure fluid in the accumulator.

The operation of the machine and particularly of the fluid pressure mechanism is apparent from the foregoing description but may be briefly summarized here. Assuming that there is sufficient pressure fluid in the accumulator for the cutting block to be maintained in its elevated operative position, the clutch 29 is tripped by means of the handle 32 and an operative cycle is initiated during which the presser arm 24 descends and strikes upon a die previously placed in a selected position upon a piece of sheet material, such as a piece of shoe upper leather, supported on the cutting block 26. While this occurs, the eccentric strap 38, which is reciprocated once during each cycle, produces a single compression stroke of the pump, the pressure fluid supplied by the pump being stored in the accumulator.

Having thus described our invention, what we claim as new and desire to secure by Letters Patent of the United States is:

1. In a press, the combination with a work support and means for applying pressure to a workpiece on said support, of fluid-operated means for moving the support into its operative position and an adjustable stop for determining the operative position of the support.

2. In a press, the combination with a work support and means for applying pressure to a workpiece on said support, of fluid-operated means for moving the support into its pressure sustaining position, an adjustable stop for determining the pressure sustaining position of the support, and a valve for controlling the operation of said fluid-operated means.

3. In a press, the combination with a work support and means for applying pressure to a workpiece on said support, of fluid-operated means for moving the support against an adjustable stop determining its operative position, and a manually operable valve for controlling the flow of pressure fluid toward and from said fluid-operated means, the valve having three positions of adjustment, in one of which the pressure fluid is admitted to the fluid-operated means, in another the fluid pressure is gradually reduced to lower the support sufficiently to adjust the stop, and in a third the fluid pressure is immediately and fully released.

4. In a press, the combination with a work support and movable means for applying pressure to a workpiece on said support, of fluid-operated means for moving the work support into its operative position, and means responsive to movement of said pressure applying means for supplying pressure fluid to actuate said fluid-operated means.

5. In a press, the combination with an adjustable work support and movable means for applying pressure to a workpiece on said support, of fluid-operated means for maintaining the support in its operative position, an adjustable stop for determining the operative position of the support, a pump responsive to movement of said pressure applying means for actuating the fluid-operated means, and a valve for releasing pressure from the fluid-operated means to permit adjustment of the stop.

6. In a press for cutting out blanks from sheet material, the combination with a vertically adjustable cutting bed and a vertically movable

presser arm adapted to apply pressure to a die placed on the sheet material supported on the cutting bed, of a fluid-operated mechanism for raising the cutting bed, the mechanism including a cylinder and a plunger of which the latter is connected to the cutting bed, a pump actuated upon movement of the presser arm, to force a pressure fluid into the cylinder to raise the plunger and the cutting bed, and a manually adjustable stop for limiting the upward movement of the piston.

7. In a press for cutting out blanks from sheet material, the combination with a vertically adjustable cutting bed and a vertically movable presser arm adapted to apply pressure to a die placed on sheet material supported on the cutting bed, of a fluid-operated mechanism for raising the cutting bed, the mechanism including a cylinder and a plunger of which the latter is connected to the cutting bed, a pump actuated upon movement of the presser arm to supply pressure fluid, a manually operable valve for determining the flow of said pressure fluid into the cylinder to raise the plunger and the cutting bed, and a manually adjustable stop for limiting the pressure movement of the plunger and thereby determining the operative position of the cutting bed.

8. In a press for cutting out blanks from sheet material, the combination with a vertically adjustable cutting bed and a vertically movable presser arm adapted to apply pressure to a die placed upon sheet material supported on the cutting bed, of a fluid-operated mechanism for raising the cutting bed into its operative position, the mechanism including a cylinder and a plunger of which the latter is connected to the cutting bed, a pump responsive to movement of the presser arm for supplying pressure fluid, a manually adjustable stop for limiting the pressure movement of the plunger and thereby determining the operative position of the cutting bed, and a manually operable valve which in one position admits said pressure fluid to the cylinder to raise the plunger and cutting bed and which in another position permits the expulsion of the pressure fluid from the cylinder to lower the cutting bed.

9. In a press, the combination with a work support and movable means for applying pressure to a workpiece on said support, of fluid-operated means for moving the work support into its operative position, a pump for supplying pressure fluid, means responsive to movement of said pressure applying means for operating the pump, and manual means for operating the pump.

10. In a press, the combination with a work support and movable means for applying pressure to a workpiece on said support, of fluid-operated means for moving the work support into its operative position, means responsive to movement of said pressure applying means for supplying pressure fluid, means for storing said pressure fluid, and a valve for controlling the flow of

the pressure fluid from said storing means to said fluid-operated means to actuate the fluid-operated means.

11. In a press, the combination with an adjustable work support and movable means for applying pressure to a workpiece on said support, of fluid-operated means for moving the support into its operative position, an adjustable stop for determining the operative position of the support, a pump responsive to movement of said pressure applying means for supplying pressure fluid, an accumulator connected to the pump for receiving and storing the pressure fluid, and a valve for controlling the passage of the pressure fluid to and from said fluid-operated means.

12. In a press, the combination with a vertically adjustable work support and movable means for applying pressure to a workpiece on said support, of fluid-operated means for moving the work support into its operative position, means responsive to movement of said pressure applying means for supplying pressure fluid, means for receiving and storing the pressure fluid, and connections between said fluid-operated means and said storing means, the storing means acting to cushion the effect of the operative engagement of the pressure applying means with the work support.

13. In a press, the combination with a work support and movable means for applying pressure to a workpiece on said support, of fluid-operated means for raising the work support into its operative position, a valve mounted in a casting and controlling the flow of pressure fluid toward and from said fluid-operated means, a spill-over chamber provided in the valve casing for receiving the pressure fluid expelled from the fluid-operated means in the exhaust position of the valve, a reservoir for the fluid, connections between the reservoir and the spill-over chamber, said connections being opened on movement of the valve into its position of pressure application to return the fluid contained in the spill-over chamber to the reservoir.

14. In a press, the combination with a work support and means movable toward an operative position to apply pressure to a workpiece on said support, a fluid-operated means for moving the support into its operative position and for sustaining it in that position against the impulse of the pressure applying means.

15. In a press, the combination with a work support and means movable toward an operative position to apply pressure to a workpiece on said support, of fluid-operated means for moving the support into its operative position and for sustaining it in that position against the impulse of the pressure applying means, and a valve for controlling the operation of said fluid-operated means.
